UNITED STATES PATENT OFFICE.

THOMAS B. LASHAR, OF FAIRFIELD, CONNECTICUT, AND THOMAS H. LASHAR, OF CHICAGO, ILLINOIS, ASSIGNORS TO ASSOCIATED SILVER COMPANY, OF CHICAGO, ILLINOIS, A CORPORATION OF ILLINOIS.

SILVER-REENFORCED TABLEWARE AND METHOD OF MAKING THE SAME.

Application filed April 18, 1925. Serial No. 24,225.

This invention relates to improvements in table-ware and the like.

The primary object of this invention is the provision of improvements in means for 5 economically and efficiently fusing or melting a precious metal filling into a depression in a base metal in order to efficiently reinforce those parts of articles which are exposed to major wear, and substantially for 10 the purpose set forth in my co-pending application Serial Number 614,982, filed January 26, 1923.

A further object of this invention is the provision of improvements in the formation 15 of table-ware or the like, embodying novel means for extra reenforcing the article at points of major wear, with a precious metal of the same characteristics as the metal with which the article is to be plated, and embodying a novel step for shaping certain 20 protuberances which anchor the precious metal reenforcement to the article.

A further object of this invention is the provision of a novel process for the formation 25 of an article of manufacture, such as a piece of table-ware, including means for forming a novel shaped depression in the base metal piece of the table-ware while it is still in its flat stock condition, and subsequently 30 anchoring precious metal in the depression in an efficient and economical manner so that after the article is bowed or formed in its die, and plated, the precious metal filling in the depression will be thinned 35 out from its central portion to the outer edges thereof; the thickest portion of the precious metal reenforcement being then disposed at the place of major wear and gradually sloping at reduced thickness to points 40 of minor wear.

A further object of this invention is the provision of an article of manufacture, such as table-ware set forth in my copending application above referred to, including a novel 45 arrangement for forming protuberances in a flat piece of base metal within a depression, filling the depression with precious metal to cover the protuberances, subsequently 50 bowing the article in a die to articulate the portion of the article in which the depression is formed so that the protuberances are rearranged with their axes in a diverging relation to more firmly anchor the

precious metal thereto, and subsequently 55 electroplating the base metal and previous metal filling with a precious metal embodying substantially the same characteristics as that of the precious metal filling.

Other objects and advantages of this invention will be apparent during the course 60 of the following detailed description.

In the accompanying drawings, forming a part of this specification, and wherein similar reference characters designate corresponding parts throughout the several views, 65

Figs. 1 and 2 are respectively plan and edge elevations of a piece of flat base metal struck in the form of a blank simulating the outline of the article.

Figs. 3 and 4 are respectively plan and 70 cross-sectional views showing the base metal after a second step has been performed thereon to provide a depression in a certain portion thereof with protuberances therein; the protuberances and depressions being 75 formed in a novel relation.

Figs. 5 and 6 are respectively plan and cross sectional views of the flat piece of base metal, after the depression therein has 80 been filled with a precious metal and fused or melted to the base metal.

Figs. 7 and 8 are respectively bottom plan and cross-sectional views of the article after 85 the same has been placed on a forming or bowing die.

Fig. 9 is a cross-sectional view of the article after being plated.

Figs. 10 and 11 are enlarged cross-sectional views, fragmentarily showing improved features of the article of manufacture at different steps in the process thereof; these views being taken substantially on the line 10—10 and 11—11 respectively of Figs. 5 and 7 of the drawings.

In the drawings, wherein for the purpose 95 of illustration is shown only a preferred embodiment of this invention the letter A may generally designate a flat piece of base metal, cut in blank, in the general outline of the article to be manufactured, and substantially 100 as is illustrated in Figs. 1 and 2 of the drawings. In the specific instance the article to be manufactured is a spoon, and the blank A includes the head portion 10 and handle portion or shank 11.

The next step in the process of forming

the article is that of die-punching the same to provide a well defined depression 13 inwardly of a side surface 14 thereof; the well defined depression 13 in the specific 5 instance providing a straight edge or shoulder 15 arranged adjacent the shank 11 at right angles to the axis of the article and with a substantially U-shaped edge 16 extending in bowed relation toward the free 10 end of the head 10. The punch with which this depression 13 is formed is so shaped that incident to the punching operation a plurality of peaked protuberances or projections 20 are provided in upstanding relation in the well defined recess 13, arranged 15 in parallel relation substantially at right angles to the plane of the base metal blank A. The punching operation so forms the depression inwardly of the surface 14, that 20 the surfaces 25 surrounding the walls 15 and 16 of the well defined depression 13 slope outwardly and upwardly from the well defined depression 13 into the plane or contiguity of the surface 14. Thus the 25 depth of the entire depression formed in the base metal A is greatest in the well defined depression 13 wherein the protuberances occur, and the depression gradually decreases in thickness along the sloping 30 surface 25 from the well defined depression 13 to the surface 14, and as can readily be seen in Figures 4, 10 and 11 of the drawings.

After the formation of the depression and the protuberances, as above described, the 35 next step is to fill the depression 13 with precious metal, of the same characteristics as the metal with which the finished article will be plated; this precious metal being provided to an amount sufficient to fill the 40 well defined depression 13 and overflow the edges 15 and 16 thereof, to cover the sloping wall 25 until a crown portion overlies the peaks of the protuberances 20 to a predetermined and sufficient depth. In this step the 45 precious metal is melted or fused into adhering relation with the base metal, and as is illustrated in Fig. 10 the exposed surface of the precious metal reinforcement or filling lies substantially continuous with the 50 exposed surface 14 of the flat stock base metal A.

At the next step in the process the base metal with the precious metal in the relation described is struck up in a bowling die 55 or other die to form the article into substantially the shape desired. For articles of table ware, such as spoons and forks, the surface 14 will be convexed by formation in the bowling die, and the precious metal 60 exposed surface will likewise be convex and lying substantially contiguous or flush with the surface 14. This step of forming the article in the bowling die is important in connection with the proper anchoring of the 65 precious metal in the depression, and inci-

dent to the heavy blow of the polished surface of the bowling die, the precious metal will slide easily and the protuberances 20 will assume a diverging relation in contradistinction to the parallel axial relation in 70 which they were disposed on the flat base metal A prior to the bowling die forming step. The protuberances 20 after the die forming step, as is illustrated in Fig. 11 75 of the drawings will be radially arranged with respect to the concavo-convexity of the article, with their axes disposed in diverging relation toward the convex side of the precious metal filling 30, and arranged in converging relation toward the concave 80 side of the article metal base portion. After this die stamping operation, it is to be noted that the precious metal 30 is of greater thickness in the central portion of the depression, and that it gradually thins toward the edges thereof, at the shallow portion of the depression which lies outwardly of the well defined depression 13 above mentioned, and the exposed outline 33 of the precious 85 metal reenforce or filling 30 will assume an irregular uneven outline substantially as is 90 illustrated in Fig. 7 of the drawings, after the die-stamping operation has been accomplished.

The article is now ready to be plated, 95 and the entire exposed surfaces both of the base metal and the precious metal filling 30 are now electroplated with precious metal having the same characteristics as the precious metal filling 30, for an even depth 100 all over the base and precious metal filling, as is illustrated in Figure 9 of the drawings.

An important feature of the process by which the article is manufactured is the 105 placing of the silver or precious metal in its fused relation on the base metal prior to bowling of the article. If the silver or precious metal were fused or melted on after the spoon had its bowl formed, the 110 heat would anneal the article and render it so soft that it would bend in use.

From the foregoing description of this invention it is apparent that an article has 115 been provided which is properly reinforced with precious metal at a point where major wear is wont to occur, substantially for the purpose set forth in my co-pending application above referred to. In the article herein described, however, the bowling die step while sufficient to permit the silver filling 120 to flow readily under the force of the blow will not have any distorting effect on the shape which the protuberances will take incident to the arcuating of the portion of the article adjacent which the depression is 125 formed, so that the protuberances will project in a diverging relation into the precious metal to more firmly anchor it. The purpose of providing the precious metal re- 130

- enforce 30 is so that after the plating of the article has been worn away, at the point of major wear where the silver or precious metal reenforce 30 is provided, the precious metal 30 will then be exposed and due to the fact that the same is of the same characteristics in quality and appearance as the plating 35, no one will detect the wear at this point of major wear. The major wear is of course over the protuberances, and after the crown portion of the precious metal reenforce 30 has worn away the peaks of the protuberances will be exposed, but will not be detected due to their minute appearance.
- 10 The place of minor wear is of course on the other surfaces of the spoon other than a place where the reenforce 30 is provided, and between these areas of major and minor wear, an intermediate wear may occur, which is greater than minor wear but less than major wear. Any liability of wearing of the base metal to exposed relation at this point of intermediate wear is obviated due to the thinning out of the precious metal reenforce 25 30 along the sloping surfaces 25, since these sloping surfaces 25 are provided immediately at the point of intermediate wear upon the article.
- 15 Various changes in the shape, size, and arrangement of parts may be made to the process and form of invention herein shown and described, without departing from the spirit of the invention or the scope of the claims.
- 20 We claim:
- 30 1. That step in the process of manufacturing articles which consists in providing a blank of base metal, die punching a depression in a surface of the base metal blank which slopes entirely about the periphery of the depression on a gradual taper into the surface of the blank in which the depression is formed, and fusing precious metal in the depression to the base metal so that the exposed surfaces of the base and precious metals are substantially flush.
- 35 2. That step in the process of manufacturing articles which consists in providing a blank of flat base metal, die punching a depression in a surface of the flat base metal blank so that the depression slopes on a gradual taper into the surface of the blank within which the depression is formed, and connecting precious metal to the base metal in the depression so that the precious metal gradually thins on the sloping surface of said depression toward the outer edges thereof.
- 40 3. That step in the process of manufacturing articles which consists in providing a blank of base metal, die punching a depression in a surface of the base metal blank which slopes entirely about the depression on a gradual taper into the surface of the blank within which the depression is formed, filling the depression and covering the protuberances with a precious metal, stamping the base metal and precious metal filling the depression in a bowling die to concavo-convexly form the base metal and precious metal filling so that the precious metal outer sur-
- 45 to said base metal so that the exposed surfaces of the base and precious metal are substantially flush, and shaping the blank in a die to form the precious metal with the base metal in the shape desired with the precious metal gradually thinning in depth toward all the outer edges thereof.
- 50 4. That process of forming an article which consists in providing a blank, forming a depression in the blank with protuberances extending upwardly therein, filling a precious metal in said depression to cover said protuberances, and forming the base and precious metals in a die to alter the conformation thereof so that the protuberances assume a diverging relation in the precious metal to anchor the precious metal in said depression to said base metal.
- 55 5. That process of forming an article which consists in providing a piece of base metal, pressing a depression in the base metal to provide protuberances extending upwardly within the depression in substantially parallel axial relation, placing the precious metal in the depression to cover said protuberances, and forming the base metal and precious metal filling the depression in a die so that the precious metal smoothly conforms to said depression in contiguous relation with said base metal surface in which the depression is formed and so that the protuberances assume a diverging relation in the precious metal to anchor the same thereto.
- 60 6. That process of forming an article which consists in providing a piece of base metal, pressing a depression in the base metal to provide protuberances extending upwardly within the depression in substantially parallel axial relation, placing the precious metal in the depression to cover said protuberances, forming the base metal and precious metal filling the depression in a die so that the precious metal smoothly conforms to said depression in contiguous relation with said base metal surface in which the depression is formed and so that the protuberances assume a diverging relation in the precious metal to anchor the same thereto, and coating the precious metal and base metal with a plating of precious metal of substantially the same characteristics as the precious metal filling the depression.
- 65 7. That process of forming an article which consists in providing a blank piece of flat base metal, stamping a depression in a plane surface thereof with protuberances extending upwardly in the depression and so that the depression slopes gradually into the surface in which the depression is formed, filling the depression and covering the protuberances with a precious metal, stamping the base metal and precious metal filling the depression in a bowling die to concavo-convexly form the base metal and precious metal filling so that the precious metal outer sur-

face lies in contiguous relation with the adjacent outer surface of the base metal and so that the protuberances assume a diverging relation in said precious metal to anchor the same in said depression.

8. That process of forming an article which consists in providing a blank piece of flat stock, stamping a depression in a plane surface thereof with protuberances extending upwardly in the depression and so that the depression slopes gradually into the plane surface in which the depression is formed, filling the depression and covering the protuberances with a precious metal, stamping the base metal and precious metal filling the depression in a bowling die to concavo-convexly form the base metal and precious metal filling so that the precious metal outer surface lies in contiguous relation with the adjacent outer surface of the base metal and so that the protuberances assume a diverging relation in said precious metal to anchor the same in said depression, and subsequently coating the base metal and precious metal filling with a precious metal having substantially the same characteristics as the precious metal filling.

9. An article of manufacture including a piece of base metal provided with a depression therein, protuberances extending outwardly of and disposed within the depression in diverging relation toward their outer ends, and a precious metal filling in said de-

pression covering said protuberances and anchored thereby in said depression.

10. An article of manufacture comprising a piece of base metal having a depression therein at a point on the article where major wear is wont to occur, said depression gradually sloping to decrease in depth as it extends toward the surface in which it is depressed, and a precious metal filling in said depression having the outer surface thereof substantially flush with the outer surface of the base metal, said precious metal being of greatest depth at its central portion and decreasing in depth along the sloping of said depression.

11. As an article of manufacture a piece of table-ware providing a base metal portion having a depression formed therein with protuberances extending upwardly in the depression in diverging relation, said depression at its edges gradually sloping toward the outer surface of the base metal in which the depression is formed, a precious metal filling in said depression anchored therein by said protuberances and of decreased thickness at the sloping portion of said depression, and a precious metal plating over said base metal and precious metal filling having substantially the same characteristics as the precious metal filling.
